[57] CLAIM

The ornamental design for an electrical connecting
plug, as shown and described.

DESCRIPTION

FIG. 1 is front elevational view of the electrical connecting plug showing to my new design;

FIG. 2 is a top plan view thereof;

FIG. 3 is a rear elevational view thereof;

FIG. 4 is a bottom plan view thereof;

FIG. 5 is a right side elevational view thereof;

FIG. 6 is a front elevational view thereof of the electrical connecting plug showing my new design coupled
with an electrical connecting socket which is shown in
broken lines for illustrative purposes only;

FIG. 7 is a top plan view thereof;

FIG. 8 is a rear elevational view thereof;

FIG. 9 is a bottom plan view thereof;

FIG. 10 is a right side elevational view thereof.
